UNITED STATES PATENT OFFICE.

FRANK S. PARKER, OF DETROIT, MICHIGAN.

OVERHEAD RAILWAY.

1,196,717.

Specification of Letters Patent. Patented Aug. 29, 1916.

Application filed November 8, 1915. Serial No. 60,202.

To all whom it may concern:

Be it known that I, FRANK S. PARKER, a citizen of the United States of America, residing at Detroit, in the county of Wayne and State of Michigan, have invented certain new and useful Improvements in Overhead Railways, of which the following is a specification, reference being had therein to the accompanying drawings.

10 This invention relates to an overhead railway, and the primary object of my invention is to provide a novel motor or running gear from which a car or carrier can be safely suspended, the motor or running gear including a truck which cannot become accidentally displaced at crossings or intersections of tracks, thus reducing accidents and delays, caused by derailment of trucks, to a minimum.

20 A further object of my invention is to provide a durable street equipment for overhead tracks, of a suspension railway system, and it is in this connection that the suspension railway system may be constructed over 25 waterways, as canals, to avoid the use of valuable lands for traffic purposes and to avoid street traffic congestion when the railway system is placed at a sufficient height for such purpose.

30 The above are a few of the objects which may be attained by the overhead railway to be hereinafter specifically described and then claimed, and reference will now be had to the drawings wherein—

35 Figure 1 is a side elevation of a portion of an overhead railway in accordance with my invention; Fig. 2 is an end view of the street equipment, partly in section, showing an end view of a motor and its car; Fig. 3 is a plan of a track intersection, and Fig. 4 is a cross sectional view taken on the line IV—IV of Fig. 1.

The street equipment comprises uprights 1 in opposed relation with the upper ends 45 thereof connected by transverse trussed frames 2. The uprights 1 are provided with inwardly projecting brackets 3 and 4, held relative to the trussed frames 2 by suspension or tie rods 5. The inner or confronting ends of the brackets 3 and 4 support track girders or runners 6 for the rails 7 of a track, said track girders connecting the sets of uprights, as best shown in Fig. 1. The sets of uprights are suitably spaced 55 apart and intermediate portions of the track girders 6 are connected to the sets of up-

rights by angularly disposed tie rods 8 which prevent the track girders 6 from sagging intermediate the sets of uprights. The rails 7 provide a track for a motor comprising a rectangular frame 9 having a longitudinal central trussed member 10. Contiguous to the ends of the frame 9 are bearing plates 11 for the bearings 12 of truck bodies 13. The bearings 12 of the truck bodies 13 are connected to the bearing plates 11 by king bolts 14, constituting pivotal means for positively retaining the bearings against the plates 11, whereby each truck body will be positively held in operative relation to the frame 9. Each truck body 13 has journal boxes 15 for the axles 16 of wheels 17 on the rails 7, thus providing what is ordinarily known as a "double truck" at each end of the frame 9. The double trucks 75 are provided with motors 18 adapted to impart movement to an axle 16 of each truck through the medium of a train of gears 19 or other power transmission device, said motors receiving electrical energy through 80 a shoe 20 adapted to contact with a third rail 21 supported by a girder 22 on the inwardly projecting bracket 3.

Suspended from the frame 9 is a car body or carrier 23 which is held by sets of suspension rods 24 passing through the car body and having the lower ends thereof connected to beams 25 on the bottom of the car body. The upper ends of the suspension rods 23 are provided with cross heads 26 having 90 trunnions 27 in bearings 28, carried by the frame 9. It is preferable to provide suspension rods at the ends of the frame 9 and intermediate the double trucks, and the cross heads 26 of the intermediate sets of suspension rods 24 are connected by diagonally disposed rods or braces 29 to the top of the car body 23. It is through the medium of the sets of suspension rods 24 and the rods 29 that the car body 23 is maintained in longitudinal alignment with the frame 9 of the motor, but allowed to swing from side to side as is essential when the motor passes over a curved section of track.

At the intersection of tracks, as shown in Fig. 3, there are converging brackets 30 supporting the connections between the rails of the track, and in conjunction with this figure of the drawings, it is to be noted that the gage of each track is less than the length of 110 wheel base of each double truck, whereby a set of wheels will always remain on a track

when passing over an intersection. It is therefore essential that the bearing plates and bearings be of considerable area, to prevent the trucks from tilting when passing over the gap between the confronting ends of the rails of the track. It is therefore perfectly safe for a double truck to travel over the gap at the intersection of the tracks.

10 When the cars are suspended some distance above a street, suitable provision, as platforms, may be made whereby passengers may enter and leave the car.

From the foregoing it will be observed 15 that the suspension of a car from between the rails of a track prevents the use of cross over rails at the intersection of tracks, and such elimination necessitates the wheel base of a truck being greater than the gage of a 20 track whereby a truck may span the gap between the confronting rails of the track.

What I claim is:—

1. In an overhead railway system, intersecting tracks devoid of cross over rails, and 25 a motor adapted to travel upon said tracks, said motor comprising a trussed frame, bearing plates at the ends thereof, double trucks at each end of said frame and having a greater wheel base than the gage of said 30 track, a bearing plate on each truck pivotally connected to the bearing plate of said frame and engaging the frame bearing plates to prevent the tilting of said trucks, and a car suspended from said motor frame.
2. In an electric overhead railway system, intersecting tracks devoid of cross over rails,

and a motor adapted to travel upon said tracks, said motor comprising a frame, bearing plates at each end thereof, and double trucks at each end of said frame having non-tiltable bearings engaging the bearing plates of said frame and pivotally connected thereto.

3. In an overhead railway system, a track, a third rail, a motor electrically driven from 45 said third rail, double trucks supporting each end of said motor, suspension rods between the rails of said track and having trunnions connecting the upper ends of said rods to said motor frame, a car body below 50 said track held by the lower ends of said rods passing through said car body, and diagonally disposed rods connecting the roof of said car body to trunnions of said suspension rods.

4. In an overhead railway system, intersecting tracks devoid of cross over rails, and a motor adapted to travel upon said tracks, said motor comprising a trussed frame, bearing plates at the ends thereof, double trucks 60 at the ends of said frame on a track and having bearings non-tiltable pivotally connected to the bearing plates of said frame, said double trucks having a wheel base greater than the gage of said track, and a 65 car suspended below said trucks.

In testimony whereof I affix my signature in presence of two witnesses.

FRANK S. PARKER.
